UNITED STATES PATENT OFFICE.

CHARLES L. HOLT, OF LAWRENCE, MASSACHUSETTS.

EXPANSION-JOINT FOR SOIL-PIPES.

SPECIFICATION forming part of Letters Patent No. 760,790, dated May 24, 1904.

Application filed August 21, 1903. Serial No. 170,242. (No model.)

To all whom it may concern:

Be it known that I, CHARLES L. HOLT, of Lawrence, county of Essex, State of Massachusetts, have invented an Improvement in Expansion-Joints for Soil-Pipes, of which the following description, in connection with the accompanying drawings, is a specification, like characters on the drawings representing like parts.

10 In flat-roof buildings it is customary to provide a rain-water box in the middle of the roof, toward which point the roof is made to slope, and this box is connected to the sewer by the soil-pipes which run through the building. Considerable difficulty has been encountered in forming a water-tight joint between these rain-water boxes and the soil-pipe, and these connections often become broken by frost, settling of the building, and from 20 other causes.

The object of my invention is to provide a form of expansion-joint between a rain-water box and a soil-pipe which may be made to be perfectly tight at all times and which will enable an iron or earthen soil-pipe which is not provided with a hub to be employed in making a connection between a rain-water box and the pipe below, thereby enabling the cut-off ends of otherwise worthless soil-pipe to be 30 employed.

In the drawings, Figure 1 is a side elevation of an expansion-joint made according to my invention. Fig. 2 is a central longitudinal section thereof on the line *yy* of Fig. 3. Fig. 3 is a cross-section on the line *xx* of Fig. 1.

35 The rain-water box *a* is provided with a metal outlet-pipe *a'*, and a metal pipe *b*, of brass or other suitable material, is connected thereto by a coupling-ring *m* or any other 40 suitable or convenient means. A piece of soil-pipe *c* is provided from which the hub has been removed, so that its upper end portion is uniform, the internal diameter of said pipe being greater than the external diameter of pipe *b*, and a coupling-sleeve *d* is placed 45 on the upper end thereof. Said sleeve is provided with an inwardly-projecting annular flange *d'* at its upper end, which is adapted to rest upon the upper end of the soil-pipe 50 and project a short distance beyond the inner

surface thereof, said pipe *b* fitting into the opening provided by said flange, and an annular packing-chamber *d''* is provided in the upper side of the flange *d'*. An inwardly-projecting flange *d''* is also provided at a short 55 distance above the lower end of said sleeve, forming a packing-chamber *d''*, the internal diameter of said flange *d''* being such that it will fit easily over the outer side of the soil-pipe *c*. Said sleeve may be secured in place 60 on the soil-pipe by set-screws *e* or any other suitable means. A gland *f* is fitted on pipe *b* above the sleeve, said gland being provided with the usual depending flange, which is adapted to fit into the chamber *d''*, in which a 65 suitable packing material is provided. A gland *g* is fitted on soil-pipe *c* below the sleeve, said gland fitting into the packing-chamber *d''*. A series of bolts *p* pass through 70 the outer flanges of the glands *f* and *g*, whereby they may be drawn together and clamped to the sleeve by means of nuts on said bolts, each gland being thereby drawn against the packing contained in its corresponding chamber, making a tight joint at these points. 75

The lower end of the pipe *b* is preferably provided with three radially-projecting lugs *b'*, and the edge portion of the flange *d'* is provided with corresponding recesses *d''*, through 80 which said lugs may be passed.

In assembling the parts the sleeve *d* is secured in position with its flange *d'* resting on the upper end of the soil-pipe *c*, with the gland *g* in position below it, and the pipe *b* is passed into the pipe *c*, its lugs *b'* being passed through 85 the recess *d''* of the flange *d'* and the pipe *b* then being turned, as illustrated in dotted lines in Fig. 3, so that said lugs are moved out of register with the recess *d''*. The gland *f* is then passed on over the upper end of the pipe *b*, and the latter is then connected to the discharge end of the rain-box. The recesses 90 *d''* and *d''* having been filled with a suitable packing, the glands *f* and *g* are drawn toward each other, making a tight joint between the 95 pipe *b* and the soil-pipe *c*.

The pipe *b* extends into the pipe *c* sufficiently to permit the former to be withdrawn from the latter as much as may be necessary to compensate for probable variations be- 100

- tween the end of pipe *c* and the rain-water box. In case the pipes *b* and *c* should separate to such an extent that the former would be withdrawn from the latter then the lugs *b'* 5 on the pipe *b* will engage the flange *d* and prevent such separation, and the sleeve *d* would then slip upon the soil-pipe *c*, the set-screws *e* being loosened after the joint is completed to permit such movement.
- 10 By this means a simple form of water-tight expansion-joint is provided which may be quickly connected and will permit of sufficient relative movement of the connected pipes to meet all requirements.
- 15 Having thus described my invention, what I claim as new, and desire to secure by Letters Patent, is—
1. A pipe connection for the purpose described comprising two telescoping pipes, a 20 coupling-sleeve on the larger pipe having an inwardly-projecting, annular flange at its upper end within which the smaller pipe is fitted, said flange being adapted to rest on the upper end of the larger pipe and having an annular packing-chamber in its upper side next the 25 smaller pipe, a gland for said chamber on the latter, said sleeve having an annular packing-chamber in its lower end next the larger pipe,

a gland therefor on the latter and means for drawing said glands together, to force them 30 into their respective chambers, substantially as described.

2. A joint for connecting two telescoping pipes comprising a coupling-sleeve fitted on the outer side of the larger pipe and having 35 an inwardly-projecting annular flange engaging the end thereof, and into which the smaller pipe is fitted, said flange having one or more notches at its edge and an annular packing-chamber on its outer side, corresponding lugs 40 on the end of said smaller pipe adapted to pass through said notches, a gland fitted on said latter pipe and entering said chamber, said sleeve having a packing-chamber at its opposite end from said flange, a gland therefor fitted on said larger pipe and means for clamping said glands to said sleeve, substantially as described.

In testimony whereof I have signed my name to this specification in the presence of two sub- 50 scribing witnesses.

CHARLES L. HOLT.
